United States Patent Office

Des. 227,744
Patented July 17, 1973

227,744

CONTAINER FOR PILLS OR THE LIKE

Walter Mitchko, 337 Elwood Road,
East Northport, N.Y. 11731

Filed Mar. 25, 1971, Ser. No. 128,209

Term of patent 14 years

Int. Cl. D9—03

U.S. Cl. D9—235

FIG. 1 is a plan view of a container for pills or the like in an open configuration, showing my new design;
FIG. 2 is a bottom plan view thereof;
FIG. 3 is a plan view thereof in a closed configuration;
FIG. 4 is a side elevational view of FIG. 3;
FIG. 5 is an end elevational view thereof; and
FIG. 6 is an enlarged cross-sectional view taken through the center of FIG. 3.

I claim:

The ornamental design for a container for pills or the like, substantially as shown.
